BONDING MACHINE AND METHOD

Daniel Belcher, Minneapolis, Minn., and Russell J. Williams, St. Louis, Mo., assignors to Bemis Bro. Bag Co., St. Louis, Mo., a corporation of Missouri

Application July 15, 1935, Serial No. 31,330

55 Claims. (Cl. 93—21)

This invention relates to a bonding machine and method, and with regard to certain more specific features to automatic apparatus for making paper bags and the like.

5 Among the several objects of the invention may be noted the provision of a method and means for manufacturing a bag which may avoid the formation of lateral outside creases in performing the operations necessary for carrying 10 out formation of the bag; the provision of apparatus of the class described which avoids the necessity of making the bag by manual means in order to avoid said outside crease; and the provision of fully automatic apparatus of this class 15 which is relatively compact and simple and high-speed in operation, and which is readily adjustable to accommodate bags of various widths, lengths, weights and materials. Other objects will be in part obvious and in part pointed out 20 hereinafter.

The invention accordingly comprises the elements and combinations of elements, features of construction, arrangements of parts, steps and sequence of steps which will be exemplified in 25 the structures hereinafter described, and the scope of the application of which will be indicated in the following claims.

In the accompanying drawings, in which is illustrated one of various possible general embodiments of the invention, with certain alternative details,

Fig. 1 is a plan view of the machine;

Fig. 2 is a side elevation;

Fig. 3 is an enlarged longitudinal section 35 showing details of a feed mechanism;

Fig. 4 is a vertical section taken on line 4—4 of Fig. 3;

Fig. 5 is a vertical section taken on line 5—5 of Fig. 4;

40 Fig. 6 is a plan view of a paper tube showing the results of a slitting operation thereon, said operation being performed on the apparatus shown in Figs. 3 to 5, or alternatively in Figs. 35 and 36;

45 Fig. 7 is an enlarged section of a revolving, tube-supporting spider, said section being a continuation to the left of the section shown in Fig. 3;

50 Fig. 8 is a plan view of certain bag positioning apparatus, the view being taken normally to the line 8—8 on Fig. 7, a certain shoe 173 and shaft 169 being broken away;

55 Fig. 9 is a vertical section taken on line 9—9 of Fig. 8;

Fig. 10 is a lateral section taken on line 10—10 of Fig. 9;

Fig. 11 is a vertical section taken on line 11—11 of Fig. 9;

Fig. 12 is a plan view of certain bag opening 5 apparatus, the view being taken normally to line 12—12 of Fig. 7;

Fig. 13 is a vertical section taken on line 13—13 of Fig. 7;

Fig. 14 is a plan view of certain hold-down 10 means, the view being taken normally to line 14—14 of Fig. 7;

Fig. 15 is a trimetric view of a tube in its condition as it reaches a glue applicator;

Fig. 16 is a vertical section taken on line 15 16—16 of Fig. 1, showing said glue applicator;

Fig. 17 is a view similar to Fig. 16 showing an alternative position of parts;

Fig. 18 is a fragmentary detail showing, under certain conditions of operation, a certain separation of drive gears for the applicator of Figs. 16 and 17;

Fig. 19 is a vertical section taken on line 19—19 of Fig. 16;

Fig. 20 is a bottom plan view of a partly finished bag showing a glue pattern impressed thereon as it leaves the glue applicator;

Fig. 21 is a fragmentary section of certain stationary and movable jaws, including a partly finished tube therebetween as it comes from the 30 glue applicator;

Fig. 22 is a trimetric view of a scoring block;

Fig. 23 is a view similar to Fig. 20 showing where certain first creases are applied;

Fig. 24 is a vertical section taken on line 35 24—24 of Fig. 1;

Fig. 25 is a horizontal half-section taken on line 25—25 of Fig. 24;

Fig. 26 is a vertical section similar to the one shown in Fig. 9 but in an advanced position so 40 as to show the operation of a first fold-over at its respective cam station;

Fig. 27 is a view similar to Fig. 23 but showing the partly finished bag as it leaves the first fold-over cam station;

Fig. 28 is a view similar to Fig. 26 showing the parts advanced to a last creaser mechanism and tube release station;

Fig. 29 is a fragmentary view similar to Fig. 23 showing a further advance in parts;

Fig. 30 is a horizontal section taken on line 30—30 of Fig. 29;

Fig. 31 is a fragmentary detail showing means for minutely adjusting the timing of the last creaser mechanism;

45

50

55

Fig. 32 is a vertical section taken on line 32—32 of Fig. 29;

Fig. 33 is a view similar to Fig. 27 but showing in dotted lines a final creasing;

5 Fig. 34 is a view similar to Fig. 15 but showing a finally glued and creased bag ready for delivery to the drying and pressing belts shown in Figs. 1 to 3;

Fig. 35 is a fragmentary view similar to Fig. 7 10 showing the re-location of certain cutters, and means for causing a forming or paster blade to effect the added function of initially positioning the tube;

Fig. 36 is a plan view of the parts of Fig. 35, 15 being taken normally to line 36—36 on Fig. 35;

Fig. 37 is a view similar to Fig. 32 but showing an alternative form of the last creaser mechanism and tube release station;

Fig. 38 is a vertical section taken on line 38—38 20 of Fig. 37; and,

Fig. 39 is an enlarged end elevation of a creaser blade of Fig. 38 showing thereon an over-centering, grab mechanism.

Similar reference characters indicate corresponding parts throughout the several views of the drawings.

Final bag product (Fig. 34)

The bag herein referred to is of the so-called 30 "satchel" type. It is preferably, though not necessarily, of a type wherein the bottom is not folded back against the body of the bag but extends symmetrically endwise therefrom. There is a central bottom crease but no outside, lateral 35 crease. It is to be noted that a bag may be made on this machine with the bottom folded against the side by eliminating the creasing operation illustrated in Fig. 33.

40 Antecedent tubular blanks (Fig. 6, without slits)

The material for making the bags is in the form of a blank paper tube pre-cut to suitable lengths 1, each length having extended from one end of one side a tab 3. Each length 1 has a 45 corresponding recess 5 in the opposite end of the tube blank on the same face as the tab 3. The tab 3 of each blank has been cut from the recess 5 of another blank. The recess serves as a means for initiating subsequent bag opening. The 50 blank 1 is glued at a side seam 7.

45 Operations to be performed (Figs. 6, 9, 15, 20, 23, 27, and 33)

The operations to be performed on said blank 55 1 by the machine herein described may be briefly summarized as follows:

1. Longitudinally slitting the tubular blank at the end which is to become the bottom of the bag (see numeral 9, Fig. 6) to provide side flaps 11 and 13, leading and trailing respectively (see also Fig. 15) and end flaps 15;

2. Bend (not crease) over the entire slitted end (Fig. 9);

3. Grip the tab 3 of the leading flap 11, the 65 same leading with respect to the direction of said bending (Fig. 9);

4. Bend back the trailing flap 13 (without the tab 3), thus forming the blank into a general T-shape and substantially flattening the bottom, the end flaps 15 turning inwardly (Fig. 15);

5. Apply a U-shape 17 of adhesive to the leading side flap 11 and end flaps 15 (Fig. 20);

6. Crease or score the end flaps 15 and side flaps 11, 13 as at 19 to define the bottom of the 75 bag (Fig. 23);

7. Fold the trailing side flap 13 against the adhesive on the end flaps 15 (Fig. 27);

8. Fold the leading side flap 11 over the previously folded trailing flap 13 (Fig. 33);

9. Crease or score the folded side flaps 11, 13 and end flaps 15 in the plane of the flat tube as at 20 (Figs. 33 and 34); and,

10. Flatten the finished bags and stack them.

Receiving and delivery table (Figs. 1-5)

10

Referring now more particularly to Figs. 1 and 2, there is shown at numeral 21 a frame having a bracket 23 upon which is formed a horizontal receiving table 25 and which frame 21 carries bearings 27 for a rotating spider assembly 29.

15

The spider 29 carries a main gear 31 outside of said frame 21, this gear being driven by means of a suitable pinion 35 from a motor drive 33. The direction of motion of the gear 31 is counter-clockwise, as shown in Figures 2 and 3.

20

A countershaft 37 in the frame 21 is driven from said main gear 31 by means of the intermediate pinion 39 and gear 41, and delivers its motion to a shaft 43 by means of a chain drive 45. The shaft 43 drives cutter rolls 47 upon each of which rolls 47 is mounted a thin cutter knife 49 of limited arcuate span. Each knife 49 passes through a groove 51 in a rotatable roller 53 for obtaining a cutting action upon material which passes between the pairs of rolls 47 and 53. Rolls 53 contact rolls 47 and are driven by gears 61 and 62 (Fig. 5).

30

The table 25 is provided with a central slot 55 within which travels the upper reach of a chain 57, the latter carrying three lugs 59. The lugs project upwardly from said slot 55 as they traverse the same. The chain 57 is driven from a gear 61 keyed to said shaft 43 (Fig. 5), said gear 61 driving a shaft 67 by means of a gear train 69. The train 69 is arranged to cause the 40 shaft 67 to move counterclockwise so as to drive the chain 57 in a direction to forwardly feed blanks which are laid on the table 25 sending them into position between the pairs of rolls 47 and 53. Suitable supporting sprockets 71 are 45 associated with the chain 57.

35

In order that the flat, paper tube blanks may be properly guided as the lugs 59 push them successively forwardly, adjustable guides 73 are used on said table 25. As shown in Fig. 1, the slot 55 is not symmetrical with respect to the guides 73, so that the lugs 59 will not contact tabs 3, (Fig. 6) but will contact next to them. It is to be understood that the blanks (without the slits 9 in them) are positioned successively on the table 25 and because of the successive advance of lugs 59, are successively fed between the pairs of rolls 47 and 53. It is further to be understood that the timing of the shaft 43 and of the shaft 67 is such that as the forward and central portions of the blanks pass between the pairs of rolls 47 and 53, the cutters 49 are not in the grooves 51. By the time that the rear portions of the blanks are between the pairs of rolls 47 and 53, the knives 49 advance into the 65 grooves 51 to cut the slits 9. It will be apparent that by relatively adjusting the lugs 59 with respect to the blades 49, slits 9 may be cut to various lengths. Relative adjustments may be effected by the frictional clamp 75 on the last 70 gear of the train 69 (Fig. 5). From the above it will be seen that after passage between the rolls 47 and 53, a slotted tube is obtained, as shown in Fig. 6.

The next problem is to suitably mount the 75

successive tube blanks thus formed in suitable position in said spider 29. This is accomplished by means of an oscillating table 77 pivoted at 79 to the bracket 23 and carrying on sprockets 81 a chain 83. The chain 83 carries a single lug 85 which cooperates within a groove 87 in a raised portion 89 of the oscillating table 77. The raised portion 89 of the table is supported on blocks 91. This table 77 also carries adjustable guides 93 having functions analogous to the guides 73. Rolls 63 draw the blanks of Fig. 6 to the oscillating table 77, the rolls being driven through a train 65.

The chain 83 is driven from its right-hand (Fig. 15) sprocket 81 by a gear drive 97 from said gear 61. Inasmuch as the final gear of this drive is on the same center as the pivotal center of the table 77, said table may be oscillated without interfering with the driving action.

Oscillation is obtained by the action of a cam 99 which is mounted on said countershaft 37. This cam 99 oscillates a spring-retumed bell crank lever 101 which, through a connecting rod 103 to the table 77, controls the latter to oscillate 25 up and down from the dotted-line position of Fig. 3 to the solid-line position shown. The purpose of this oscillation is to have the off-take end of the oscillating table 77 travel with the ends of certain pairs 105 of pockets 111 on the spider 29, successive oscillations of the table 77 coinciding with successive passages of successive pockets. Thus successive slotted blanks are fed from the oscillating table 77 into successive pockets 30 105, the slotted ends extending from the pockets.

Adjustable receiving pockets and clamping jaws (Figs. 7, 9, 11, 12, 13, 16, 21, and 28)

The spider 29 is shown per se in Fig. 7 and 40 comprises a set of stationary jaws 107 which rotate counterclockwise (Fig. 7) and lead certain movable jaws 109. Behind the jaws 107, 109 are located said pairs 105 of pockets 111. Each member of each pair 105 consists of a strip 111 of U-shaped section, having a flared outer mouth 113 (Figs. 9 and 11). Each pocket carries bearings 115 which ride freely on cross guides 117. Each pocket-member 111 also carries a control nut 119 with which cooperates a lead screw 121, the latter 45 having right- and left-hand threads respectively for engaging respective ones of said nuts 119, so that by a given rotation of the lead screw 121, the respective pockets of a pair may be adjusted for greater or less bag widths.

In order that adjustments of the pockets for 55 bag widths may be carried on simultaneously throughout all of the six pairs on the spider 29, each lead screw 121 is provided with an endwise gear 123. This gear 123 is shown in Figs. 7, 11, 60 16, 17, and 24, and is controlled through an idler 125 from a main adjusting gear 127 which is adapted to be locked to the spider 29 by means of an index locking gear 66 (Figs. 8 and 24) also carried by the spider 29. The index locking gear 65 66 is provided with suitable spanner-wrench, adjusting holes 133. It will be appreciated that the six gear trains 123, 125 are associated with the common gear 127. The gear 127 normally turns with the spider 29 and in essence, merely forms 70 a mechanical connection between all of the gears 123, 125. Gear 66 is adapted to be locked after an adjustment is made by means of suitable tapered, pull-up device 129 thereon so that a given manual adjustment is maintained (with certain 75 exceptions to be hereinafter described).

Exceptions mentioned in the last paragraph above come about by reason of the gears 123 and the adjusting lead screws 121. The screws 121 are mounted in frames 131 which are the supports for the movable jaws 109, said frames 131 being pivoted on the same centers as the gears 125 (Figs. 7, 9, 11, 16, and 17). It will thus be seen that whenever a frame 131 rocks to provide motion for a movable jaw 109, that the respective gear 123 has a planetary action with respect to 10 its then fixed gear 125. Gear 125 cannot move at this time because gear 127 is locked by gear 66. This planetary action when the jaw 109 opens is adapted, through the respective lead screw 121 to cause the momentary separation of 15 the pockets 111, as when said pockets get into the dotted-line position shown in Fig. 3. Then, when the respective jaw 109 later closes, as for the reasons to be described, the pockets draw closer together. This action permits of a slight 20 variation in bag widths and insures an easy reception of any bag by the pockets 111. Then, after the bags are in the pockets 111, the pockets return to their optimum adjusted position to better align the bags for greater accuracy in subsequent operations. At the same time that this automatic and temporary adjustment is effected, there is no interference with manual adjustment of the pockets 111 by way of loosening the 25 locked gear 127 and making the manual adjustment. Furthermore, the automatic, temporary adjustment is effective regardless of what manual adjustment has been made.

Each frame 131 has an extension 135 therefrom carrying a follower 137 (Figs. 9 and 11) 35 for contacting with a stationary cam 139 on the side frame 21, so that as the spider 29 rotates, the follower 137 traverses the cam 139 to cause a suitable oscillation of the frame 131 and hence a suitable movement of the respective, trailing, 40 movable jaw 109. The cam 139 is so designed that the opening action desired occurs at the time that the pairs 105 of receiving pockets 111 reach the dotted-line position shown in Fig. 3. Then the respective movable jaw 109 opens and 45 closes as the respective receiving region is traversed. During this time (as the jaw 109 opens and closes) the said temporary spreading action of the pockets 111 takes place.

Depth of entry adjustment (Figs. 7, 9, 10, and 11) 50

As shown in Figures 7 and 9, the depth of entry of the blanks into their respective pockets is adjustable. This is accomplished in each segment of the machine by means of a rack 141 slidable 55 in guides 143 (Figs. 9 and 10), the latter being associated with the frame 131. The rack 141 carries a removable stop 145 for the shorter lengths of blanks. The rack 141 is controlled by a meshed pinion 147 on a shaft 149. Shaft 149 reaches outwardly of the frame 131 to a gear 151 which is connected to a main adjusting gear 153 through an intermediate idler gear 155. Like the gear 127, the gear 153 normally moves with the spider 29 and is held in a given position by 65 means of an indexing and locking gear 157 (Figs. 12 and 28). The gear 157 is locked by means of a taper, pull-up device 159 and is provided with spanner-wrench-engaging adjusting holes 161. Thus there is provided a common means for 70 adjusting the effective depths of all pockets 111.

In order to accommodate various lengths of longer blanks, the stops 145 may be removed and use may be made of deeper stops 163 at the lower ends of the racks 141. Thus two ranges 75

of adjustments are available for bag lengths. The adjustment, as in the case of the lateral pocket adjustment, is also subject to planetary action of the gear 151 about gear 155 (Fig. 24). 5 Inasmuch as the gear 151 is on the shaft 149 and shaft 149 controls the action of pinion 147 (Figs. 10 and 15), there will be a movement of the rack 141 together with the stops 145 and 163 upwardly each time that the jaws 107, 109 close, and a 10 recession each time that they open. The advantage of this is that at high speeds the blanks in being thrown against the stops 145 or 163, tend to bounce away, and this epicyclic take-up assures a final accurate positioning of the bag 15 extensions from the jaws 107 and 109.

From the above it is evident that as the receiving pockets 111 approach the dotted-line position shown in Fig. 3, the respective jaws 109 open 20 away from the jaws 107 to expose the said pockets 111 mounted on the frames 131 that carry the jaws 109. At the same time the pockets 111 temporarily separate and the table 77 is depressed. At this time a bag slips off the table 77 and into the members 111 as the table and the 25 pockets rise. When the table reaches a level position, the jaws begin to close and the pocket members 111 approach one another. It will be understood that the bags accurately seat on one or the other of the stops 145 or 163. Thus each 30 bag is accurately positioned in a radial direction and is clamped behind the rearward slotted end by means of the jaws 107, 109 (see dotted lines A, Fig. 7).

35 *Laying over the blank (Figs. 7-9, 13)*

An extension 165 from the frame 21 supports a gear train 167 and a cross shaft 169 driven thereby. The train 167 is driven from the main gear 31. A bail 171 is mounted on the shaft 169 10 and is revolved thereby in the clockwise direction indicated in Fig. 7, the same coming tangent to closed jaws 107, 109, as they pass. The gear train 167 has such a value that the bail 171 has a high-speed motion and is so timed that an arcuate 15 shoe cross piece 173 of the bail reaches its tangent position to the closed jaws 107, 109 as they pass. Inasmuch as the jaws are carrying a bag (dotted lines, A, Fig. 7), the bail 171 strikes the bag extension from the rear and lays it over forwardly in the direction of motion of the spider 29 (see Fig. 9). This has the effect of laying the 20 slotted end of the bag down upon the stationary jaw 107. As the edges of the jaws 107 and 109 are relieved by rounded portions 175, the bag is 25 not bent, creased or otherwise permanently deformed where laid over.

35 *Tab gripper (Figs. 7-9, 12, 13, 16, and 24)*

Before the bail 171 leaves the position shown 60 in Fig. 9, a tab gripper 177 is caused to advance to hold the tab 3 as shown in Fig. 12. Each gripper 177 is mounted on a cross shaft 179, the latter being rotatable in bearings 181 affixed on an adjusting ring 183 which is slidably mounted on the spider 29 (see Fig. 13) and is held in a given adjustment by means of slots 182 and holding screws 184. 65

From each shaft 179 extends an arm 187 which carries a spring-returned follower 189 cooperating 70 with a fixed cam 191. The cam 191 is so positioned and formed that as the bail 171 leaves the turned-over bag extension, the gripper 177 comes down upon the tab 3 so as to hold the bag in position (Fig. 9) until later released (Fig. 24).

75 By adjusting the ring 183, various extensions

of bags from the spider may be accommodated. The peripheral width of the fixed jaws 107 is such as to accommodate these various extensions.

Partially arranging the bag flaps (Figs. 12 and 13) 5

It will be seen that when a tab 3 is gripped, this has the effect of holding down the forward bag flap 11. The rearward bag flap 13 tends to spring up slightly, in the case of many bags, thus tending (but not completing) the drawing in of 10 the side portions to effect the flap formation 15, 15. In order that this process may be definite, an air blast pipe 193 is located as shown in Figs. 12 and 13. The air blast emanating from the nozzle 195 in part 193 is directed into the semi- 15 open tube end and blows back the rear flap 13.

Flattener and first holder for bag flaps (Figs. 7, 13, 14, and 15)

As the forwardly bent and open tube end advances in the face of blast (Fig. 13), it approaches certain first, hold-down and positioning strips 197. These strips 197 present a barrier, which as the trailing flap 13 approaches the same causes said flap 13 to be turned back. Backward 25 bending of the flap 13 causes the side flaps 15 to tend to be pulled in as shown in Fig. 13. The further back that the slot 13 is bent, the more said slots 15 are pulled in until they tend to approach the position shown in Fig. 15. However, 30 the ideal condition of Figure 15 is not reached until the end flaps 15 pass under tucking rolls 199. The rollers 199 and positioning strips 197 are adjustable.

35 *Second holder for the arranged bag flaps (Figs. 7, 14, 15, and 16)*

After the blanks pass the tucking rolls 199, they are driven under a set of second hold-down bars 201, peripherally mounted about the spider 40 29. A mounting rod for bars 201 is shown at numerals 203. As shown in Fig. 14, said second hold-down bars 201 are spaced from one another and are laterally controllable in position by means of a right- and left-hand lead screw 205 45 under control of a handwheel 206. The lead screw is mounted in the side frame 21, as are the guide supports 203. The hold-down bars 201 maintain the conformation of the tube about as shown in Figs. 14 and 15 after it leaves the tucking rolls 199, said conformation being continued 50 until a point B (Fig. 7) is reached.

Adhesive applicator (Figs. 7 and 16-20)

Before the blanks leave their positions under 55 the bars 201, a glue-applying station is traversed. This station comprises a glue reservoir 207 carrying suitable glue and into which dips a pickup roll 209 driven by a gear 211 and removable idler 213, the latter meshing with a gear 215. The gear 215 is fastened to shaft 231 and the shaft extends outside of the frame 21 where it is provided with a gear 249 which meshes with main gear 31.

The idler 213 carries a transfer roll 217 which 65 contacts the pickup roll 209 and is adapted to deliver a sheet of glue to the U-shaped surface of an applicator roll 218. The said U-shaped surface is formed by means of bars 219 which are adjustable and replaceable by similar ones 70 of various lengths to accommodate various bags. The shaft which carries the applicator roll 218 is mounted in a swingable frame 221.

The gear 249 which also is swinging is driven 75 from the main gear 31 at all positions of frame

221 and gear 215 drives gear 213 in all these positions. The shaft 223 to which the frame 221 is fastened, is rotatably held in the side frame 21. There is also a swingable arm 225 freely borne, on shaft 223 having a follower 227 which engages with a cam 229 fastened to the shaft 231. The shaft 231 supports both the gear 215 and the applicator roll 218.

As the applicator shaft 231 is driven, there is a tendency for the arm 225 to be moved counter-clockwise (Fig. 16) under action of cam 229. A spring 233 connects the frame 221 and the arm 225 (Fig. 19) and normally biases the arm to force the follower 227 against the cam 229. Thus under normal operation, the arm 225 is intermittently swung counter-clockwise and returned clockwise as the applicator roll 217 rotates, this action being due to the operation of cam 229 on the follower 227. As the applicator roll 217 rotates, the U-shaped member 219 applies a U-shaped impression of glue to the end slots 15 and the forward slots 11, as shown in Figure 20.

Detector mechanism for adhesive applicator (Figs. 16-19)

It may sometimes occur that in a given set of jaws 107, 109, a bag is missing. It would not be desirable to have the applicator 219 apply glue to the working parts of the machine not covered by a blank. In order to prevent this, a detector finger 235 cooperates with a peripheral slot 237 which traverses the outermost surfaces of all parts associated with the rotating spider 29. When a bag blank is in position, this slot is partially covered by the turned-down end of the blank. Thus, when the bag approaches the detector finger 235, the finger will be raised out of the slot 237. The finger 235 controls a cross shaft 238 having thereon a crank 239, controlling a connecting rod 241, and latch arm 243. The latch arm 243 interlocks with a notch 245 on the lever 225 when the finger 247 of the latch is up; detector 235 down (Fig. 17). Thus, if a bag is missing, the detector finger 235 remains down and the latch finger 247 remains up so that when the cam 229 tends to drive the arm 225 to the right (Fig. 17) under action of follower 227, a reaction will be set up so that, instead of the arm 225 swinging to the right as in Fig. 16, the frame 221 will swing to the left. This raises the applicator, as shown in Fig. 17, so that it clears the machine parts and separates the applicator 219 from roll 217, thus preventing an over-charge of adhesive on the first successive blanks. When a blank is in position the detector 235 is raised and hence depresses interlock finger 247 to permit arm 225 to rock, thus avoiding the reaction for lifting the frame 221.

In view of the fact that the parts connected with the frame 221 are relatively heavy, the friction between the latch 247 and notch 245 is great enough that the strength of the paper blank which touches the detector finger 235 may not be enough to open the latch. For this reason, an extension 246 is provided from the latch 247 with which cooperates a cam 248 carried on the shaft 231. The parts 246 and 248 cooperate once per revolution, just before a blank approaches the detector 235 (provided the blank is present). This means that if there had been an interlocking arrangement, due to the previously missing blank, the linkage 239, 241, 247 will be rendered free of the weight of the frame 221, so that the approaching blank may readily hold it free. On the other hand, if no blank is in position to ad-

vance, the detector finger 235 will descend to set the latch 247 back into interlocked position with the latch 245.

When the frame 221 is lifted, the clearance between gears 249 and 31 is increased but they do not unmesh. Thus the timing is never interfered with by the detector action.

In order to obtain an accurate application of glue, the applicator roll 209 is made adjustable as indicated at 210. On the outside of the frame, 10 the shaft 223 is provided with an arm 251 carrying an adjusting screw 253 which bears against the frame 21. Thus the applicator roll 218 may be adjusted in or out in its relationship to the passing blanks. From the above it will be seen 15 that the form of Fig. 20 is obtained wherein the U-shaped swath of glue has been applied. This is the condition of the blank when it leaves the glue applicator station and approaches point 20 "B" (Figs. 16 and 17).

Double creaser (Figs. 7, 8, 21-24 and 34)

The next operation consists in applying the creases 19 shown in Fig. 23. It is to be understood that the creases 19 are not such as will appear 25 on the side of the bag, but are those shown in Fig. 34 at the lower end of the bag. Provision is made for this operation by providing the ends of the jaws 107, 109 with creaser block inserts 255 (Fig. 22). The inserts 255 are held in recesses 257 and are reversible therein, both end-for-end and/or top-for-bottom. Holding screws 259 co-operate with centrally located threaded holes 261 in the creaser blocks. Equivalent quick-change holding means may be used. Each block 255 is provided with one set of longitudinally arranged grooves 263 which are non-symmetrically arranged with respect to the screw holes, so that only by reversing a block 255 end-for-end, different relative positions of the grooves 263 are 40 obtained. On the opposite side of the block 255 is a second set of non-symmetrically arranged grooves 265. These grooves 265 are gaged at different distances from the block edges than the set 263, thus providing a still greater variety on the possible positions of grooves.

The purpose of the grooves 263 or 265, in general, is to cooperate with creaser blades 267 (Figs. 24 and 25) which are adjustably clamped to a cross shaft 269 borne in crossheads 271 of lateral guide slots 273 in the frame 21. The guide slots 273 are enclosed endwise by caps 275 which rotatably support a control shaft 277 operable from a handle 279. The control shaft 277 carries eccentrics 280 linked with rods 281, each of which is in turn connected with the shaft 269 by a connecting link 283. Springs 285 normally press the crossheads 271 forwardly so that the shaft 269 with its creaser blade 267 is pressed forwardly.

Operation of the lever 279 results in withdrawal of the creaser blades backwardly, against the action of springs 285. The purpose of the withdrawal is to permit of freely adjusting the relative angular positions of the blades 267. The shaft 269 is normally driven from the main gear 31 by means of a gear 287 when the latter is in its right-hand position wherein the crossheads 271 are against stops 289. The stops 289 serve to limit the inward motion of the creaser blades 267 so that when the latter rotate, they properly co-operate with the slots 263 or 265 in the creaser block inserts 255 so that the blank ends which lie over the creaser blocks 255 are creased without damage to the material by cutting or 75

the like. The proper action is shown in Figs. 21 and 24.

At the time that the double creasing action takes place, it is necessary to release the tab 5 3 from the grip of the tab gripper 177. This is done by causing the follower 189 to contact with a stationary cam 291 (Fig. 24). This gripper only temporarily opens, and recloses shortly after ceasing its operation. It is not again 10 reopened until the other stationary cam 191 is reached. In connection with the above operation it should be noted that the tube or blank has left its position under the hold-down bars 201 which end at point B, thus exposing the 15 whole lower face (with glue thereon in U-shape) to the action of said creaser blades 267, as shown in Fig. 23).

First flap folder and paster (Figs. 7, 24, and 26)

20 The next procedure is to lay down the trailing flap 13 over the upper ends of the legs of the U-shape of glue on the bottom of the partially formed bag. This is accomplished by a paster blade 293 which is located on a support 303. The 25 support 303 is controlled by a crank 295 on shaft 296. The arm 295 carries a follower 297 engaging with a fixed cam 299. The forming or paster blade 293 needs normally to be in a position within the periphery of the spider so that it does not 30 interfere with adjacent operating parts. Hence this blade 293 must first be forced outwardly from its inner position before it is forced forwardly to the position shown in Fig. 26. To do this there is provided a stationary cam 301. This 35 cam 301 is cooperated with by the pivoted support 303. Thus, as the crank 295 swings, the blade 293 is first directed outwardly, and thereafter by action of the bell crank 295 is driven forwardly (see Figs. 8 and 26).

40 *Third holder (Figs. 7, 26, 28, and 30)*

After the follower 297 leaves the cam 299, the paster blade 293 moves quickly backwardly and inwardly to clear. Before this stage, the 45 flaps 15 have passed under a third set of hold-down bars 307 similar to the hold-down bars 201, similarly mounted on supports 309 and similarly adjusted by a right- and left-hand lead screw 311 controllable from a handwheel engaging portion 313 (Fig. 30).

Second flat folder and paster (Figs. 7, 27, 28, 30, and 33)

During folding over of the trailing flap 13, the 55 leading flap 11 has sprung up to the position shown in Figure 26, this being due to the creasing operation. Backward folding of this leading flap 11 from the position shown in Fig. 27 to that shown in Fig. 33 is accomplished by a 60 spring leaf 314 extending laterally, the same being mounted upon a bar 315 fastened to opposite sides of the frame 21. The result of this operation is shown in Fig. 33 with the exception that Fig. 33 shows a crease which is not yet in 65 the bottom when it leaves the spring blade 314.

Presser (Figs. 29 and 30)

In the condition of Fig. 33 (without the central crease), the bottom face of the nearly completed bag blank is engaged by presser rolls 317 which are pressed against the bottom by springs 70 319. The presser rolls 317 are sectional and are splined to their supporting shafts 321 and by means of set screws 323 are adapted to be assembled into various widths and suitably posi-

tioned for optimum operation on various blank widths. The shafts 321 carry gears 325 which are driven from the main gear 31.

Final creaser (Figs. 7 and 28-33)

The final operation consists in applying the central bottom crease 20 (Fig. 33). The device for this purpose consists of a cross shaft 327 having openings 329 therein adjacent to arms 331, the latter being fixed to the shaft 10 327. The arms 331 are provided with guides 333 for accommodating slidable crossheads 335 which carry and control the direction of movement of creaser blade 337. Connecting rods 339 are articulated to the blade 337 and also to 15 cranks 341 mounted on a crank shaft 343 borne in said arms 331. The crank shaft 343 carries a pinion 345 which meshes with a sector gear 347, the latter being carried on an arm 349 which is pivoted at 351 to one of the arms 331. The 20 arm 349 carries a follower 353 which cooperates with a stationary cam 355 carried on the side frame 21.

The shaft 327 carries an endwise gear 357 which is adjustably fastened thereto by means of 25 the slot-and-bolt fastener combination 359 controlled by adjusting jackscrews 361 (Fig. 31). This gear 357 meshes with the main gear 31 and thus the shaft 327 is driven.

The operation of the last creaser per se consists in the continuous turning of the shaft 327 which turns the arms 331 and causes the follower 353 to traverse the cam 355. This oscillates the arm 349 as the shaft rotates and causes the sector 347 to rotate the pinion 345 at a high rate of 35 velocity. The pinion 345 moves from a position at 90° counterclockwise of the Fig. 29 position on its own axis through 180°, so that the crossheads 335 are driven quickly outwardly and inwardly and driving the blade 337 in between the 40 passing jaws 107, 109, and out again. Fig. 29 shows a mid-stroke position. At this time, the jaws are slightly and temporarily opened by contact of the follower 137 with an adjustable fixed cam 363. This cam 363 is an auxiliary to 45 the cam 139 and is placed at the region of said cam 139 which causes final opening of the jaws 107, 109. It is desired to delay the final opening slightly after the operation of cam 363 so that after withdrawal of the creaser blade, there is a 50 slight inward motion of the jaws to positively determine a good bottom crease.

From this point, the follower 137 rides up on the high point of the cam 139 to open the movable jaw 109 from the fixed jaw 107, thus releasing 55 the finished bag, as illustrated in Fig. 28.

The purpose of the last creaser mechanism is to obtain a positioning of the creaser blade adjacent to the jaws 107, 109 and as the jaws open slightly, to obtain the quick inward thrust of the 60 blades 337 between the jaws to effect the crease 20 and cause the flaps 11 and 13 to become positioned adjacent one another as shown in Fig. 34.

Take-off conveyor and flattener (Figs. 1-3 and 7)

The released bag falls upon a conveyor belt 365 which has an upper reach 367 frictionally engaging a lower reach 369 of a second presser belt 371. The belts after a period of contact 70 again separate at point 373 where the bags are ejected as shown in Fig. 2. This has the effect of pressing the bags into a relatively flat condition and determining proper setting of the glue. The presser belt 371 is driven by an independent drive 75

375 and the belt 365 is driven by means of said frictional engagement with the belt 371.

Operation in general

The operation of the device is as follows:

Blanks such as shown in Fig. 6 are successively laid on the table 25 and are successively driven by the lugs 59 through the cutter rolls to be rearwardly slitted by the cutters 49 and delivered to the oscillating table 71. At the same time, the spider 29 is rotating to bring successive open jaws 107, 109 up to the end of the oscillating table. The lug 85 aids gravity in pushing blanks into the then presented pairs 105 of pockets 111 (Fig. 3).

The pockets, as they receive the blanks, spread apart slightly, temporarily and automatically, to permit free entry, and then approach one another to properly position the blanks. At the same time one or the other of the stops 145, 163 determines the amount that the slitted ends of the bags project from the spider 29.

As the spider rotates, the projecting ends of the blanks reach the rotating bail 171 which forces the extending ends of the blanks forwardly (without creasing) to be gripped by the tab gripper 177.

Next, the rearward tab 13 tends to spring up and is further blown up by the action of the jet of air from the nozzle 195. This places the open end of the tube in position to be cooperated with by the first hold-down strips 197. Thereafter the tucking rolls 199 are encountered which force the bottom of the partly finished bag into the position shown in Fig. 15. These are not presser rolls. Thereafter the second set of hold-down bars 201 are approached. The blank then passes into position under said bars and advances through the glue applicator 217 where the U-shape of glue is applied as shown in Fig. 20.

Advance is next made to the creaser blades 267 which, by cooperating with the creaser blocks 255 apply the first creases 19 shown in Fig. 23.

Then the paster blade 293 is raised outwardly and forced forwardly to force down the trailing flap 13 into contact with the legs of the U-shaped glue. It will be seen that the inward position of the blade 293 has been necessary up to this point so as to clear the paster and creasing mechanisms and other adjacent parts.

During the first creasing operation, the leading flap 11 has sprung up to the position shown in Fig. 26 so that when the spring 314 is reached, said flap is folded back into the position as shown in Fig. 33.

Next, the flat bottoms shown in Fig. 33 without the crease 20 are pressed by the presser rolls 317.

Next, the final crease 20 is accomplished by the quick-acting creaser blade 337. At this time, the holding jaws separate slightly to admit the blade and thereafter separate more widely to eject the bag which is dropped upon the conveyor belt 365. The belt 365 cooperates with belt 371 to press and eject the finished bag from the machine (Fig. 2).

Alternative slitting construction (Figs. 35 and 36)

In Figs. 35 and 36 is shown alternative means for providing the slits 9 in the blanks and for laying the same forwardly to be gripped by the grippers 177. These alternative forms substitute for the rolls 47, 53 and cutters 49 on the one hand, and the bail 171 on the other hand.

In this alternative form, a gear train 375 is

used for driving gudgeons 377 mounted rotatably in the frame 21, the gudgeons 377 having fastened thereto supports 379 for supporting rotatable cross-shafts 381. The shafts 381 carry arms 383 carrying followers 385 which cooperate with fixed cams 387. By this means, when the frames 379 are rotated, the shafts 381 are oscillated.

One of the shafts 381 carries a cutter backing plate 389 which is in the position shown in Fig. 35 as the extension of the bag from jaws 107, 109 approaches the position shown in Fig. 35. The other shaft 381 carries an arm 391 which in turn carries a pair of cutters 393 which cooperate with suitable recesses in the plate 389. The mechanism is so timed that as the bag extension advances to the Fig. 35 position, the blades 393 and the plate 389 approach one another at a radial position to cut the bag slits 9. After this, the plate 389 and blades 393 separate and move out of the path of further movement of the tube extension.

In order that different blank lengths may be accommodated, the blades 393 are adjustable.

Another feature of this modification is that the paster blade 293 is used for laying down the bag extension on the fixed jaw instead of the bail 171. This is simply accomplished by providing another fixed cam 395 with which the paster blade 293 cooperates just as the plate 389 and blades 393 separate. This throws the paster blade 293 first out and then forward, as hereinbefore described in connection with its former pasting function. This places the tab blank beneath the tab holder where it is gripped, as already described. After the cam 395 is traversed, the paster blade mechanism sends the paster blade back into its returned and inward position to clear the subsequent peripheral operating means.

Alternative last creasing construction (Figs. 37 to 39)

In Figs. 37 to 39 is shown another form of last creasing mechanism in which a positive operation is obtained for high-speed output. This mechanism comprises a blade 401 having a thin central portion 403 and thick, rectangular end portions 405. The central portion 403 is for the purpose of entering between the jaws 107 and 109 when they slightly open at the last creasing station, as already described. The end portions 405 are bolted to control links 407 positioned on opposite sides of the spider 29 and within the sides of the frame 21.

Each link 407 is pivoted at 409 to a driving crank 411. Each driving crank 411 is borne on a stub shaft 413, one shaft on each side of the machine. Each stub shaft 413 is supported in a bearing 415 formed in the sub-frame 439 and in an outboard bearing 417 carried on a bracket 418 bolted to said frame 21 as at 419.

On the right side of the machine (Fig. 37) the respective shaft 413 carries a pinion 421 meshing with the main gear 31. This pinion 421 has adjustably bolted thereto a second pinion 423 which meshes with a gear 425 on a jack shaft 427. The jack shaft crosses between the side pieces of the frame 21 clear of the spider 29 and carries at its opposite end a gear 428 which meshes with a gear 429 on the other stub shaft 413. Thus both cranks 411 are driven at the same angular velocity and the relative positions of both with respect to the gear 421 may be adjusted to the same phase, as indicated by the adjusting fasteners 431 between gears 421 and 423.

The links 407 are pivoted at 433 to swing links 75

435, the latter being pivoted at 437 to adjusting members 439. The adjusting members 439 swing on the same centers as gears 423 and 429 and carry locking members 441 working in arcuate 5 slots 443 for adjusting the relative positions of center 437. It will be understood that the members 439 may be dispensed with, if the centers 437 can be accurately enough predetermined. The adjusting members 439 also carry the bearings for 10 the shaft 427.

It will be understood that the adjusting members 439 may be made to adjust only the center 437 and that the jack shaft 427 may be borne directly on the sides of frame 21, instead of in the 15 auxiliary extension from said adjustable member 439. There is a slight advantage in bearing the shaft 427 in the adjustable member 439 from the viewpoint of maintaining proper tolerances in the manufacture of the device.

20 From the above it will be seen that the cranks 411 are rotated at the same angular velocity and in phase and that each crank with the respective link 407, link 435 and frame member 439 forms a so-called, four-bar linkage. This linkage is so 25 proportioned including suitable extension of the link 407 as at 448, that the end portion of the blade 403 traverses the general path shown in dotted lines at 447. At the same time this mechanism provides that the plane of the blade shall 30 approximately follow the plane lying between jaws 107 and 109 as these jaws travel around with the spider 29. It will be noted that the plane between the jaws 107 and 109 does not remain parallel in any two consecutive positions and 35 while the plane of the blade does not exactly follow the successive planes between the jaws 107 and 109, it does so quite substantially, and enough so that the blade is accommodated snugly between the jaws in their semi-open position 40 as the jaws pass the final creasing station. At the same time the swinging action of the link 407 drives the blade 403 in between the jaws 107 and 109 as shown in solid lines in Fig. 38. Driving the blade 403 between the jaws 107 and 109 45 while they carry the T-shape blank, results in providing the bag form shown in Fig. 34, as hereinbefore described.

After the blade 403 is driven between the jaws 107 and 109 the maximum extent (shown in Fig. 50 38) it is thereafter withdrawn as it further traverses the path 447.

In order that the bag may be positively withdrawn from its position behind the jaws 107 and 109, the over-centering mechanism shown in Figs. 55 38 and 39 is used. This comprises a lever 449 pivoted at one end 405 of the blade 403 and articulated at 450 to a slider 452 carried in a swivelling bearing 456 and normally pressed outwardly by means of the spring 451. The spring 60 457 over-centers the lever 449, either to the solid-line position shown in Fig. 39, or to the dotted-line position. The lever 449 controls a cross shaft 453 which carries holding fingers 455 which, when the lever 449 is in the solid-line position (Figs. 38 and 39) clamp down on one lower edge of the bag, against the flat back of the blade 403. In the dotted-line position, the fingers 455 are in open position and do not clamp anything.

70 Control of the lever 449 to either over-centered position is accomplished by means of dogs 451 and 459 carried on the frame 21. Assuming that the fingers 455 are normally in open position when they traverse the left-hand reach of the path 447 (Fig. 38), the lever 449 strikes the

upper dog 457 and is over-centered to its solid-line position, just as the blade 403 reaches its maximum depth of entry between the jaws 107 and 109. Then when the blade 403 is withdrawn, the fingers 455 having clamped the bag, is positively withdrawn. As the linkage proceeds in its movements, the dotted-line position thereof is finally reached in its downward movement (Fig. 38) with the bag in the dotted-line position, and delivered to the upper reach 367 of the 10 belt 365. It is now time to release the bag from the blade 403, and this is done by the lever 449 striking the dog 459 and over-centering to the dotted-line open position. The moving belt 367 carries off the bag, as the link 407 recedes with 15 the blade 403.

The gears 423 and 425 are timed so that the rising blade 403 meets the next set of jaws 107 and 109 at the proper time in the cycle.

The advantage of this alternative form of last 20 creaser mechanism is that the blade is more slowly and positively driven in and withdrawn from between the jaws 107 and 109 to effect creasing. There is no sudden action, which is better from the viewpoint of reduced wear on the machine. 25 The smoother action is due to the blade 403 being permitted to travel with the jaws 107 and 109 for a longer period of time over which slower reciprocation may be effected to perform the creasing operation per se. Furthermore, the 30 bag is positively withdrawn from its position behind the jaws 107 and 109. Also, the plane of the blade, while operating between the jaws 107 and 109, rotates in the same sense, or at least 35 not in the opposite sense, as said jaws, so as to accurately enter between them. Hence the machine may be designed for high-speed operation with assurance that there will be no lag of any parts, due to resiliently controlled members. At 40 the same time a high degree of simplicity is achieved in carrying out the ends in view.

It is to be understood that the form of bag herein, described as being creaseless on the side, is the preferable form for paper bags. However, in the case of fabric, paper lined bags or the like, 45 it is sometimes desirable that the final creasing operation illustrated in Figs. 28 to 33 be eliminated and the flat bottom face of the bag be rotated through 90° against one bag side. This has the effect of producing a side crease, but in 50 the class of bag referred to in this paragraph such a crease is not objectionable. If side creases are not objectionable, it is to be understood that the rounding at the corners of the jaws 107 and 109 may be eliminated.

It is to be understood throughout the specification and drawings, that all followers are properly held to their cams by suitable spring-return means or the like. These have not been shown in all instances in order to avoid complications in the drawings. Their construction, application and use are obvious.

In order that the feeder mechanism shown in Fig. 3 will be adjustably timed with respect to the rotary receiving spider 29, the sprocket 42 (Fig. 65 3) is made angularly adjustable on the shaft 43. The same adjustment may be effected by other means.

In view of the above, it will be seen that the several objects of the invention are achieved and 70 other advantageous results attained.

As many changes could be made in carrying out the above constructions without departing from the scope of the invention, it is intended that all matter contained in the above description or 75

shown in the accompanying drawings shall be interpreted as illustrative and not in a limiting sense.

We claim:

5. 1. In a bonding machine, a continuously rotating spider, spaced receiving pockets substantially radially arranged on said spider and adapted successively to pass a given point, and receiving means for blanks and for directing them at a 10 point of discharge into said pockets as the pockets move comprising a blank support having simultaneous movement at said point of discharge toward said pockets and substantially tangential thereto.

15. 2. In a bonding machine, a rotating spider, spaced receiving pockets radially arranged on said spider and adapted successively to pass a given point, a table for receiving tubular blanks, cutters associated with said table adapted to rearwardly 20 slit the blanks as they successively advance, and oscillating means for receiving the slotted blanks and directing them into said pockets as the pockets move.

25. 3. In a bonding machine, a rotating spider, spaced receiving pockets radially arranged on said spider and adapted successively to pass a given point, a table for receiving tubular blanks, means associated with the table for advancing blanks, cutters associated with said table adapted to rearwardly 30 slit the blanks as they advance, oscillating means for receiving the slotted blanks and directing them into said pockets as the pockets move, and means associated with the oscillating table for advancing slotted blanks.

35. 4. A bonding machine comprising a rotating spider, a plurality of pairs of pockets substantially radially arranged on said spider, operable, movable jaws beyond the outer, receiving ends of said pockets, means for opening said jaws as the pairs of pockets successively pass a given point, whereby said pockets are exposed to receive blanks.

40. 5. A bonding machine comprising a rotating spider, a plurality of pairs of pockets arranged on said spider, relatively movable jaws beyond the outer ends of said pockets, means for opening said jaws as the pairs of pockets successively pass a given point, whereby said pockets are exposed to receive blanks, and means for automatically causing the pockets to move to more 45 freely accommodate blanks as the jaws open.

45. 6. A bonding machine comprising a rotating spider, a plurality of pockets arranged on said spider and having receiving ends, relatively movable jaws beyond the receiving ends of said pockets, means for opening and closing said jaws as the pockets pass a given point, whereby said pockets are exposed to receive blanks, and means limiting the depth of entry of blanks into the 50 pockets so that portions extend from the jaws after closure.

55. 7. A bonding machine comprising a rotating spider, a plurality of pairs of pockets arranged on said spider, relatively movable jaws at the outer ends of said pockets, means for opening and closing said jaws as the pockets pass a given point, whereby said pockets are temporarily exposed to partially receive blanks, and means co-operating with the closed jaws for performing 60 operations upon the parts of the blanks extending therefrom.

65. 8. A bonding machine comprising a rotating spider, a plurality of pairs of pockets substantially radially arranged on said spider, relatively movable jaws beyond the outer ends of said

70. pockets, means for opening said jaws as the pairs successively pass a given point, whereby said pockets may receive blanks, and means responsive to opening of the jaws for causing a temporary separation of the pockets so as to freely receive the blanks and thereafter coming together to snugly hold the same, said jaws closing as the pockets come together.

75. 9. A bonding machine comprising a rotating spider, a plurality of pairs of pockets radially arranged on said spider, relatively movable jaws beyond the outer ends of said pockets, means for opening said jaws as the pairs successively pass a given point, whereby said pockets may receive blanks, means responsive to opening of the jaws for causing a temporary separation of the pockets so as to freely receive the blanks and thereafter to snugly hold the same as the jaws close, and means for simultaneously adjusting all pockets without interfering with the temporary separating action.

80. 10. A bonding machine comprising a rotating spider, a plurality of pairs of pockets arranged on said spider, relatively movable jaws at the outer ends of said pockets, means for opening said jaws as the pairs successively pass a given point, whereby said pockets may receive blanks, means responsive to opening of the jaws for causing a temporary separation of the pockets so as to freely receive the blanks, manual adjusting means for determining pocket capacity, both as to depth and width of blank, and means for simultaneously adjusting all pockets either as to depth or width without interfering with the temporary separating action.

85. 11. A bonding machine comprising a rotating spider, fixed jaws on said spider, jaws movable with respect to the fixed jaws, frames pivoted to the spider for mounting the movable jaws, pairs of receiving pockets on the respective frames, means for adjusting the distances between receiving pockets on the frame adjustable from a common point and comprising respective gear trains, said frames being pivoted to the said spider at points including the center of at least one gear of the respective train, means for adjusting all trains whereby a common adjustment may be made of all receiving pockets, a temporary adjustment being automatically effected upon oscillation of the frames by planetary action in the respective train, and automatic means for causing said oscillation.

90. 12. A bonding machine comprising a rotating spider, a plurality of pairs of receiving pockets thereon, means for adjusting the depths of said pockets from a common point and means for adjusting the widths thereof from another common point.

95. 13. A bonding machine comprising a rotating spider, a plurality of pairs of receiving pockets thereon, means for adjusting the depths of said pockets and the widths thereof from common points respectively, and means for effecting cyclic, automatic adjustment as to width only, during operation of the machine, said automatic adjustment being constant for all manual adjustments.

100. 14. In a bonding machine, a rotating spider, fixed jaws on said spider, movable jaws pivoted to said spider and associated with said fixed jaws, receiving pockets arranged inwardly of the jaws, means for temporarily opening said movable jaws, means to insert a blank into each pocket, said pocket limiting blank insertion to a depth effecting some extension of the blanks from the

jaws when closed, means for reclosing said jaws after insertion of the blanks, and means for subsequently laying the extending portions of the blanks over respective ones of said jaws.

5 15. In a bonding machine, a rotating spider, relatively movable jaws on said spider, receiving pockets arranged inwardly of the jaws, means for temporarily relatively opening said jaws, means to effect the insertion of blanks into said pockets, 10 means to limit insertion so that there is some extension of the blanks from the respective jaws, said jaws reclosing after insertion of the blanks, means for subsequently laying the extending portions of the blanks over one of said jaws, and 15 means for holding against a jaw one portion of the laid-down portions.

16. In a bonding machine, a rotating spider, fixed jaws on said spider, movable jaws pivoted to said spider and associated with said fixed jaws, 20 receiving pockets arranged inwardly of the jaws, means for temporarily opening said movable jaws to permit the insertion of a slotted blank into each pocket, the pocket limiting blank insertion to cause extension from the jaws of the 25 slotted portions of the blank, said jaws reclosing after insertion of the blanks, means for bending the extending portions of the blanks over one of said jaws, and means for laying back a portion of the bent portion to present a substantial working surface peripherally of the spider for subsequent operations thereon.

17. In a bonding machine, a rotating spider, means for bending and means holding down extending blanks comprising pivoted arms, followers 35 on said arms, at least one fixed cam cooperating with said followers as the followers move, to operate said holding means, means pivotally supporting said arms, and adjustable means for adjusting said pivotal supporting means with respect to said spider, whereby various extensions 40 of blanks may be held down after bending.

18. In a bonding machine, a rotating spider, fixed jaws on said spider, movable jaws pivoted to said spider and associated with said fixed jaws, 45 receiving pockets arranged inwardly of the jaws, means for temporarily opening said movable jaws, means to insert blanks into said pockets, the depths of the pockets causing some extension of the blanks from the jaws, said jaws reclosing after insertion of the blanks, means for subsequently bending the extending portions of the 50 blanks over one of the respective jaws, holding means for holding the bent-over portions of the blanks against the respective jaws comprising pivoted arms, followers on said arms, and at least one fixed cam cooperating with said followers as the followers move, to operate said holding means.

19. In a bonding machine, a rotating spider, fixed jaws on said spider, movable jaws pivoted to said spider and associated with said fixed jaws, receiving pockets arranged inwardly of the jaws, means for temporarily opening said movable jaws to permit the insertion of blanks into said pockets, 60 the depths of said pockets causing some extension of the blanks from the jaws, said jaws reclosing after insertion of the blanks, means for subsequently bending the extending portions of the blanks over respective ones of said jaws, holders 65 for the bent-over portions of the blanks against the respective jaws comprising pivoted arms, followers on said arms, at least one fixed cam cooperating with said followers as the followers move, to operate said holding means, means pivotally supporting said holders, and adjustable 70

means for adjusting said holder supporting means with respect to said spider, whereby various extensions of blanks from the jaws may be held down after bending.

20. In a bonding machine, a rotating spider, 5 receiving pockets thereon to permit the insertion of blanks, the depths of the pockets effecting blank extensions from the spider, jaws for holding the blanks inside the extensions, means for subsequently bending the extending portions of the 10 blanks over said jaws, holders for the bent-over portions of the blanks which are against the jaws comprising pivoted arms, followers associated with said arms, at least one fixed cam co-operating with said followers as the followers 15 move, to operate said holding means, means pivotally supporting said holders, and adjustable means for adjusting said holder supporting means with respect to said spider, whereby various extensions of blanks from the jaws may be accommodated.

21. In an automatic bonding machine, a rotating spider, means for substantially radially positioning on the spider slotted tubular blanks with outwardly extending portions, means for manipulating said extending portions to form surfaces arranged as T shapes in connection with the remainders of the tubular portions of the blanks, means for converting said surfaces into bag bottoms in the tubular blanks as the spider rotates, 30 means for creasing said bottoms in the plane of the blank and means for pressing the portions of the bottoms adjacent the creases into juxtaposition, substantially in the planes of the blanks.

22. In a bonding machine, a rotatable spider, 35 means for slitting a tubular blank to form side and end flaps, means for clamping said blank in a substantially radial position in said spider, a portion of said blank having the flaps thereon extending from the spider, means for bending all 40 flaps, means for holding an advance flap, means for turning back a trailing flap, means to place said flaps and end flaps in a plane substantially normal to the remainder of the blank, means for applying adhesive to a plurality of said flaps, 45 means for creasing the flaps parallel to the plane of the remainder of the blank, means for folding the trailing and leading flaps against the other flaps, and means for creasing all of the flaps in the plane of the remainder of the blank.

23. In a bonding machine, a rotating spider, substantially radial pocket means associated therewith for receiving a flat tubular blank, relatively movable jaws adapted to clamp said blank and permit an extending portion, means for slitting said blank, means for arranging the slitted portions of the blank flatwise and substantially normal to the remainder of the blank, means for applying adhesive to the flat surface thus exposed, means for folding certain portions of said 60 surface against other portions thereof, means for finally creasing the surface so that it is broken into two surfaces, and means for forcing said two surfaces adjacent to one another so that said flatwise surface is arranged in two portions substantially in the plane of the remainder of the blank.

24. In a bonding machine, a rotating spider, substantially radial pocket means associated therewith for receiving a flat, tubular blank, relatively movable jaws adapted to clamp said blank 70 and permit an extending portion, means for slitting said blank, means for arranging the slitted portions of the blank flatwise substantially normal to the remainder of the blank, means for applying adhesive to the flat surface thus ex- 75

posed, means for double scoring the surface, means for folding portions beyond the scores of said surface against other portions within the scores, means for creasing the surface so that it is broken into two surfaces, means for forcing said two surfaces adjacent to one another so that said flatwise surface is again arranged in two portions substantially in the plane of the remainder of the blank.

10 25. In a bonding machine, a rotating spider, substantially radial pocket means on said spider adapted to receive a tubular blank, clamping jaws exteriorly of the pocket means for clamping said blank and permitting an extending portion therefrom, means for slitting the blank at what is the extending portion whereby incipient flaps are formed, means for bending over all flaps substantially against the jaws, means for gripping one flap against a jaw, means for forcing back another flap against a jaw, whereby the flaps are arranged in a plane substantially normal to the remainder of the blank, means for applying adhesive to certain of the flaps, means for relatively folding the flaps in said plane to form a 25 closed bag bottom, means for creasing the plane of the flaps comprising a creaser blade, means for advancing said blade substantially in the plane of the blank, means for simultaneously, partially opening said jaws whereby the unitary 30 plane of the flaps is broken into two, and means for thereafter flattening the finished bag.

26. In apparatus of the class described, a spider assembly having a peripheral groove in the external parts thereof, means for holding over said 35 groove a surface to which adhesive is to be applied, rotary means adapted to apply adhesive to said surface as it passes, means for driving said rotary adhesive means from the spider assembly, a swinging mount for said rotary adhesive 40 means, a cam rotatable with the adhesive applying means, an arm normally freely oscillated by said cam, a latch normally permitting free oscillation of said arm when a surface is in position over said groove to receive adhesive but 45 otherwise interfering with the motion of said arm, a detector cooperating with the groove when said surface is not present, and means whereby the latch is set by the detector to interfere with the arm when no surface is present, whereby the 50 reaction by contact of said arm with the latch, in connection with said cam, causes the adhesive applying means to be raised to clear the spider where it is exposed by the absence of said surface.

27. In apparatus of the class described, a rotating spider, means including jaws associated therewith adapted to hold blanks in position so that peripheral operating surfaces are presented over said jaws, creaser blocks set into said jaws beneath said peripheral surfaces, rotating creaser 60 blades cooperating with said blocks to apply spaced creases in said surfaces, said creaser blocks having reversible outer and inner faces, said faces carrying grooves non-symmetrically arranged with respect to the center lines of the 65 blocks.

28. In apparatus of the class described, a rotating spider, means including jaws associated therewith adapted to hold blanks in position so that peripheral operating surfaces are presented over said jaws, creaser blocks set into said jaws beneath said peripheral surfaces, rotating creaser blades cooperating with said blocks to apply spaced creases in said surfaces, said creaser blocks having reversible outer and inner faces, 70 said faces carrying grooves non-symmetrically ar-

ranged with respect to the center lines of the blocks and at different edge distances on the respective faces, said blocks being also reversible end for end, whereby a maximum plurality of positions of said grooves may be obtained.

29. In apparatus of the class described, a rotating spider, means including jaws associated therewith adapted to hold blanks in position so that peripheral operating surfaces are presented over said jaws, creaser blocks set into said jaws beneath said peripheral surfaces, rotating creaser blades cooperating with said blocks to apply spaced creases in said surfaces, said creaser blocks having reversible outer and inner faces, said faces carrying grooves non-symmetrically arranged with respect to the center lines of the blocks, said blocks being also reversible end for end, whereby a maximum plurality of positions of said grooves may be obtained, and means for relatively angularly adjusting said creaser blades. 20

30. In apparatus of the class described, a rotating spider, jaws associated therewith adapted to hold blanks in position so that peripheral operating surfaces are presented exteriorly covering said jaws, creaser blocks associated with said 25 jaws beneath said peripheral surfaces, spaced rotating creaser blades cooperating with said grooves to apply spaced creases in said surfaces, said creaser blocks having adjustable creaser grooves, and means for relatively adjusting the 30 rotating creaser blades.

31. In apparatus of the class described, a rotating spider, jaws associated therewith adapted to hold blanks in position so that peripheral operating surfaces are presented exteriorly covering said jaws, creaser blocks associated with said 35 jaws beneath said peripheral surfaces, spaced rotating creaser blades cooperating with said grooves to apply spaced creases in said surfaces, said creaser blocks having adjustable creaser 40 grooves, means for relatively adjusting the rotating creaser blades, and means for manually withdrawing the rotary blades from cooperation with the grooves.

32. In apparatus of the class described, a rotating spider, means associated with said spider for holding a tubular blank in part in substantially radial positions and in part with peripherally presented surfaces, a rotary frame driven from said spider, a slid blade associated therewith, 50 a crank shaft held by said rotary frame, at least one connecting rod extending from crank shaft to said blade, a follower associated with said crank shaft, a stationary cam with which said follower cooperates, and means for rotating the 55 entire frame whereby said follower traverses said cam to cause reciprocation of said blade toward said surface.

33. In apparatus of the class described, a rotating spider, means associated with said spider for holding tubular blanks partly in substantially radial positions and in part presenting peripheral surfaces, a rotary frame driven to rotate from said spider, a slid blade associated therewith, a crank shaft held by said rotary frame, at least 60 one connecting rod extending from crank shaft to said blade, a follower associated with said crank shaft, a stationary cam with which said follower is associated, whereby said follower traverses said cam to cause reciprocation of said 65 blade, the timing between the spider and the frame being such that when said peripheral surface is presented opposite the blade the blade is moved to a position such that the same is directed in its frame normally to said surface and in 70 75

the plane of the portion of the blank which is held by said jaws.

34. In apparatus of the class described, a rotating spider, means associated with said spider for holding tubular blanks in part in substantially radial positions and in part with peripherally presented surfaces, a rotary frame driven from the spider, a slideable blade associated therewith, means for successively directing the blade in a direction substantially normal to said surfaces and in the planes of the portions of the blanks which are held by said jaws, and means for reciprocating the blade each time that a surface is presented.

15 35. In apparatus of the class described, a rotating spider, means associated with said spider for holding tubular blanks in part in substantially radial positions and in part with peripherally presented surfaces, a rotary frame driven from the spider, a slideable blade associated therewith, means for successively directing the blade in a direction substantially normal to said surfaces and in the planes of the portions of the blanks which are held by said jaws, means for reciprocating the blade each time that a surface is presented, and means for opening the blank holding means as the blade meets the respective surface.

36. In a bonding machine, a rotating spider, jaws adapted to hold a blank in a substantially radial position, a portion of the blank extending from the jaws, slitting means driven from the spider comprising a pair of shafts revolving about an axis, follower means associated with said shafts, fixed cams cooperating with said follower means, one of said shafts carrying slitting elements cooperable with an extending portion of a blank, and the other shaft carrying other slitting elements cooperable with the first-named slitting elements, the blank extension being slitted upon being positioned between the slitting elements, said cams being designed to separate the slitting elements as the slitted extension advances further.

45 37. In a bonding machine, a rotating spider, jaws associated therewith adapted to temporarily open to radially receive tubular blanks and subsequently to close to hold them with radially extending portions, means for slitting said extending portions, means carried within the periphery of said spider adapted to advance outwardly and forwardly to lay down the extending portion, means for holding one portion of said extending portion against a jaw, means for forcing back another portion to said extending portion, whereby a peripheral surface is presented, holding means for maintaining the character of said peripheral surface after its preliminary formation, means for applying adhesive to said peripheral surface, means for double creasing said surface, said laying over means advancing outwardly and forwardly to bend one portion of said surface against the adhesive on the other portion, means for bending back along the other crease another portion of the surface, ironing means, and a last creasing means adapted to apply a crease to the peripheral surface in the plane of the non-extending portion of the blank.

70 38. In bonding apparatus, a rotating spider, jaws on said spider for holding the ends of tubular blanks in substantially radial positions, a blade normally lying within the outermost portions of the jaws, a rocking means movable with the spider, a cam cooperable with the rocking means to oscillate the same to move the blade

tangentially at a predetermined interval, means pivoting the blade to the rocking means, a follower associated with said blade, and a cam cooperating with said follower on the blade to control the angular position of the blade, whereby when said cam is contacting, said blade is moved outwardly and forwardly to function to bend said extending portion.

39. The bonding method for making bags from flat tubular blanks comprising slitting a blank to form side and end flaps, clamping the blank to hold the same to effect a projecting portion, manipulating the side flaps respectively in opposite directions, and positioning them opposite one another substantially in a plane angularly located with respect to the clamped portion of the blank, whereby the side flaps are drawn inwardly approximately into said plane of the end flaps, applying adhesive, folding the side flaps one over the other against the end flaps in said angular plane, creasing the flat parts substantially in the plane of the remainder of the blank to form two surfaces of the said plane, and placing said surfaces adjacent one another and in the plane of the remainder of the blank.

20 40. The bonding method for making bags from flat tubular blanks comprising slitting a blank to form side and end flaps, clamping the blank to hold the same to effect a projecting portion, manipulating the side flaps respectively in opposite directions, and positioning them opposite one another substantially in a plane normal to the clamped portion of the blank, whereby the side flaps are drawn inwardly approximately into said plane of the end flaps, applying adhesive, folding the side flaps one over the other against the end flaps in said normal plane, creasing the flat parts to form two areas, hinging said areas at the crease to positions substantially in the plane of the remainder of the blank and adjacent one another, the clamped blank being moved from operating point to operating point while the flaps are in said substantially normal plane and before they are finally creased.

45 41. The bonding method for making bags from flat tubular blanks comprising slitting a blank to form side and end flaps, clamping the blank to hold the same to effect a projecting portion, manipulating the side flaps respectively in opposite directions, and positioning them opposite one another substantially in a plane normal to the clamped portion of the blank, whereby the side flaps are drawn inwardly approximately into said plane of the end flaps, applying adhesive, folding the side flaps one over the other against the end flaps in said angular plane, creasing the flat parts to form two areas, hinging said areas at the crease to positions substantially in the plane of the remainder of the blank and adjacent one another, the clamped blank being moved in a circular path from operating point to operating point when the flaps are in said substantially normal plane.

55 60 65 70 75 42. A creaser mechanism comprising means for holding a blank in substantially T-shape and moving the same, comprising a pair of moving and relatively movable jaws, means for driving said jaws, a four-bar linkage including a driving crank, a control link, and a controlled link pivoted to said driving crank and control link, a blade carried by said controlled link, said four-bar linkage being so proportioned that said blade moves along with the jaws and reciprocates therebetween while the jaws move so, and means for

slightly separating said jaws to permit the blade to reciprocate therebetween.

43. A creaser mechanism comprising means for holding a blank in substantially T-shape and moving the same, comprising a pair of moving and relatively movable jaws, means for driving said jaws, a four-bar linkage including a driving crank, a control link, a controlled link pivoted to said driving crank and control link, a blade carried by said controlled link, said four-bar linkage being so proportioned that said blade moves along with the jaws and reciprocates therebetween while the jaws move so, means for slightly separating said jaws to permit the blade to reciprocate therebetween, gripping means associated with the blade adapted to automatically grip an edge of the blank against the blade to positively withdraw the blank from the jaws, and means for opening said gripping means at a predetermined point prior to its return to the next operation between jaws.

44. A creaser mechanism comprising means for holding a blank in substantially T-shape and moving the same, comprising a pair of moving and relatively movable jaws, means for driving said jaws, a four-bar linkage including a driving crank, a control link, a controlled link pivoted to said driving crank and control link, a blade carried by said controlled link, said four-bar linkage being so proportioned that said blade moves along with the jaws and reciprocates therebetween while the jaws move so, means for slightly separating said jaws to permit the blade to reciprocate therebetween, gripping means associated with the blade adapted to automatically grip an edge of the blank against the blade to positively withdraw the blank from the jaws, means for opening said gripping means at a predetermined point prior to its return to the next operation between jaws, and means for so mounting at least one of the links of the four-bar linkage that the action of the blade may be accurately adjusted.

45. A creaser mechanism comprising means for holding a blank in substantially T-shape and moving the same, comprising a pair of moving and relatively movable jaws, means for driving said jaws to rotate, a creaser blade, means for moving said blade so that it is movable along with the jaws and reciprocates therebetween while so movable, the plane of the blade simultaneously rotating in the same sense as the jaws, and means for slightly separating said jaws as the blade reciprocates therebetween.

46. A creaser mechanism comprising means for holding a blank in substantially T-shape and moving the same, comprising a pair of moving and relatively movable jaws, means for driving said jaws to rotate, a creaser blade, means for moving said blade so that it is movable along with the jaws and reciprocating therebetween while so movable, the plane of the blade simultaneously rotating in the same sense as the jaws, and means for slightly separating said jaws as the blade reciprocates therebetween at substantially the same angular velocity.

47. In a bonding machine a rotating spider, a plurality of pairs of pockets on said spider, and means for opening and closing the pockets, depth limiting devices in said pockets, means for temporarily receding said limiting devices as a predetermined position is passed by the pockets when open and means for again advancing said devices as the pockets pass said positions and close.

48. In a bonding machine a rotating spider, a plurality of pairs of pockets on said spider, means for opening and closing the pockets, depth limiting devices in said pockets, means for temporarily receding said limiting devices as a predetermined position is passed by the pockets while in open position, and means for again advancing said devices as the pockets pass said positions and close, the apparatus for moving said devices comprising a mechanism responding to 10 pocket movement.

49. A bonding machine comprising a rotating spider, relatively movable jaws therein adapted to receive blanks therebetween and move said blanks, gripping means mounted at the periphery of said spider adapted to manipulate portions of the blanks extending from the spider, and means for simultaneously adjusting said grippers, whereby various blank extensions may be accommodated.

50. In a bonding machine, a rotating spider, receiving means arranged in said spider for receiving relatively flat blanks having end flaps and side flaps, means associated with the spider for turning the end flaps on the blanks into a plane at right angles to the plane of the respective blank, peripheral hold-down means for said end flaps which laterally clear the side flaps on the blank, and means operable between said hold-down means for manipulating said side flaps into 30 the planes of the end flaps.

51. In a bonding machine, a continuously rotating spider, spaced blank-receiving pockets substantially radially arranged on said spider and adapted successively to pass a given point, an oscillating member arranged adjacent to the spider, a flexible belt on said oscillating member having a conveying surface movable toward the discharge end thereof, and means for oscillating said member, the oscillations being timed so that the discharge end of the oscillating member intermittently assumes, over a substantial range, approximately the tangential velocity of the receiving ends of said pockets, said belt meanwhile passing blanks into said pockets.

52. In a bonding machine, a rotating spider, means for substantially radially positioning on the spider tubular blanks with outwardly extending portions, means for manipulating said extending portions to form respective peripheral surfaces, means for manipulating said surfaces to form a closed bag bottom thereat, and means for subsequently creasing each of said peripheral surfaces in the plane of the radial portion of the respective blanks, and positioning the peripheral portions on opposite sides of the respective crease adjacent one another and in the plane of the respective blank.

53. In a bonding machine, a clamp for holding a tubular blank with an outward extending portion, means for manipulating said extending portion to form a T-shape with respect to the clamped portion of the blank, said clamp forming a working surface for the cross surface of the T-shape of the blank, means for manipulating said cross surface of the blank to form a closed bag bottom, means for creasing said cross surface at its juncture with the remainder of the blank, and means for positioning the portions of the cross surface on opposite sides of the crease into 70 the plane of the remainder of the blank and adjacent one another.

54. In a bonding machine, a set of clamping jaws for holding a tubular blank with an outward extending portion, means for manipulating said

extending portion to form a T-shape with respect to the portion held in the jaws of the blank, said jaws when closed forming at their ends a working surface for the cross surface of the T-shape
5 of the blank, means for manipulating said cross surface of the blank to form a closed bag bottom, means for creasing said cross surface at its junction with the remainder of the blank by separating the jaws and inserting a creaser therebetween,
10 and means for positioning the portions of the cross surface on opposite sides of the crease in the plane of the remainder of the blank and adjacent one another.

55. In apparatus of the class described, a moving support, holding means associated therewith
15

adapted to hold a blank in a T-shaped position and including a peripheral operating surface presented over said holding means, a creaser block beneath said operating surface and having a plurality of grooves therein, a movable creaser 5 blade cooperating with said creaser block at a groove with the blank therebetween to apply a crease in the surface of the blank, and means for relatively adjusting the movement of said creaser blade with respect to the movement of the support, whereby the position of a crease may be adjusted without necessarily adjusting a creaser block.

DANIEL BELCHER.
